CARD TABLE

Charles W. Mayer, Rochester, N. Y.

Application May 31, 1933, Serial No. 673,643

2 Claims. (Cl. 273—136)

The present invention relates to playing tables and it particularly relates to card tables which are suitable for playing bridge and other two, three or four hand games.

Card tables as at present constructed are usually of non-metallic construction and with flat square tops and folding legs, one being usually positioned at each corner. The sides of the table are provided with wooden lips, which usually project slightly above the playing surface of the table and extend substantially below the bottom of the table to form a recess where the legs may be placed.

In utilizing these tables considerable difficulty has been experienced in handling the cards, due to the fact that the surface of the table which does not permit of ready movement of the cards without excessive wear thereon. The surfaces of the tables have usually been made of fabric with the result that there is considerable cohesion between the face of the card and the table, preventing ready slipping and playing thereof. Moreover, the lip at the end of the table will usually catch the edge of the card in being drawn adjacent to the player and prevent such cards from being readily lifted into the player's hand.

In addition, it is usually customary to serve liquid refreshments during the game and very frequently some of such liquid will spill onto the table. Most of the playing tables, due to their construction, have a slightly concave form with the result that such liquid will spread over the playing surface and will wet the cards and cause the table to be moist or damp for a considerable period of time. This will not only ruin the deck of cards but will interrupt the game.

An object of this invention is to provide a playing table which will be of inexpensive, durable and light construction and which will permit of ready handling and playing of the cards, particularly in regard to lifting the cards from the table to the player's hand.

Another object is to provide a card playing table which simultaneously may be used for the dispensing of liquid refreshments, without great possibility of any spilled liquid flowing over or causing moistening of the playing surface, and without danger of wetting the cards being played.

Other objects will be obvious and will appear during the course of the following specification.

In accomplishing the objects of the present invention it has been found most satisfactory to provide the usual square card playing table designed for four-handed games such as bridge, with an elevated central portion. This elevated central portion should preferably extend over the major portion of the table but should not extend to the edges thereof at any place.

Preferably, sufficient space should be left at the edges adjacent the player below the elevated

central portion for stacking or suitable placement of the cards which have been taken up during the play. The central portion is preferably of circular form and may be desirably slightly domed toward its center, but other forms of elevated centers may be utilized. Preferably the elevated center is positioned symmetrically in respect to the center of the table.

At each corner of the table there is preferably provided an enclosure in which liquid refreshments may be placed and which will prevent seepage or flow of any liquid toward other parts of the table.

In construction, the table may be provided with a top having a wood or laminated base. For example, layers of fabric or fibrous material impregnated and saturated with a resin which will harden under the effect of heat and pressure may be applied to the surface of the metal and the resultant top then placed on the table.

Although not generally desired, in some cases the top may be made of metal preferably covered with an insulating material which may be pressed rigidly onto the metal base or combined therewith to form a unitary whole. In some instances, the elevated central portion of the table may be placed thereon as a separate individual element.

By corrugating the table top or by doming it as previously described, the table not only will be stronger and more durable but, in addition, it will be easier to remove the cards from the table and to grasp them with the fingers at the edges thereof.

The above and other objects will appear more clearly from the following detailed description, when taken in connection with the accompanying drawings, which illustrate a preferred embodiment of the inventive idea.

In the drawings:

Fig. 1 is a perspective view of the table with the legs unfolded in normal or operative position.

Fig. 2 is a side sectional view of a modified top construction with the legs in folded position.

Fig. 3 is a side sectional view of a modified top construction.

Figs. 4 and 5 show another embodiment in top and side sectional view, respectively, Fig. 5 being taken upon the line 5—5 of Fig. 4.

In the figures the top 10 is provided with the supporting legs 11, provided with the brackets 12, which may be folded under the table as indicated in Fig. 2.

As shown in Figs. 1 and 2 the top 10 is preferably made of a single sheet of material which is provided with a central elevated portion 13 and with ridge portions or ribs 14 and 15. The elevated portion 13, together with the ribs 14 and 15 will form a very rigid and durable struc-

ture which is preferably bowed or convexed upwardly.

The table top 10 may be provided with the depending edge 16, which, as indicated in Fig. 2, is reinforced by the slat 17. The elevated portion 13 of the table may be provided with the corrugations 18 as indicated which may either be circular as indicated in Fig. 1, or transverse.

It is evident that the elevated portion 13 will 10 conveniently serve for the playing of cards and that the cards, due to the corrugated roughened surface 18, will slip with relative ease to the edges 20 of such elevated central portion 13 where they may be lifted by the players. Due to the 15 construction of the central portion of the table 13 the cards will slip most readily and will not adhere thereto.

In the relatively depressed portions 21 adjacent each player the cards or tricks may be 20 conveniently stacked when they have been removed from the central playing portion 13. The corner portions formed within the ridges 14 and 15 and outside of the elevated central portion 13 will conveniently serve for the reception of 25 glasses or other containers for liquids and if any liquid spills there will be no danger of it spreading over the playing surface 13 nor the stacking surface 21.

It will be noted that the cards may be most 30 readily removed from both the central elevated portion 13, as well as from a stacking portion 21 over the edges 20 and 16 respectively, since these edges are not provided with lips to catch the edges of the cards.

35 In one embodiment to which the invention is not restricted, it was found satisfactory when the table was made about 30 inches square, while the central elevated portion was made about 20 inches square, leaving a stacking place 21 of about 5 inches in depth.

The corrugations or wavy effect 18 on the elevated portion 13 may be conveniently prepared with a depth of 0.01" and may be about $\frac{1}{16}$ inch wide, center to center. It has been found most 45 convenient to elevate the central portion of the table about $\frac{3}{4}$ " over the stacking portions 21, which is somewhat more than the thickness of a normal finger, and the ridges 14 and 15 about one-half of this distance.

50 In the embodiment of Fig. 3 a table of ordinary construction 30 may be employed and upon this table may be conveniently placed the center element 31. The center elevated element 31 may have a surface 32 shaped similar as at 18 55 on the surface 13 in Figs. 1 and 2, and if desired, it may be provided with a backing 33 of wood or other material preferably to increase its weight.

The bottom of the backing 33 is provided with 60 the knobs 34 serving as legs to desirably position the elevation on the playing table. To the edges of the table are preferably nailed or otherwise connected at 35 the flexible edging 31 which extends preferably slightly below the bottom of 65 the knobs 34 so that it will closely and frictionally contact the top 39 of the table.

Fig. 3 illustrates diagrammatically how the invention of the present application may be conveniently applied to a wide variety of present 70 table constructions without reconstruction.

In Fig. 4 the table is provided with a central

elevated portion 75 which is centrally dome-shaped and crowned, as indicated upon Fig. 5 at 85 and symmetrically located in respect to the square shaped table base 76.

As shown in Figs. 4 and 5 the shoulder 78 elevates the center portion 75 above the relatively horizontal flat portion 80 of the base 76. The table top shown in Figs. 4 and 5 may be made up of laminated wood or of layers of fibre combined with a plastic material, said layers of fibre 10 being compressed in a hydraulic press to form a satisfactory table top.

The table top shown in Figs. 4 and 5 may be circularly corrugated as shown in Fig. 2 but such corrugations should be very fine and very closely 15 spaced together, as for example with a depth of 0.005" and a width of 0.035".

The dome-shaped or crowned elevated center, such as shown in Figs. 4 and 5, aids the sliding of the cards and enables the players to pick them 20 up much more easily. It is noted that corner partitions, such as shown in Fig. 1, are not utilized since these may be omitted if desired.

Although the top as shown in Figs. 4 and 5, may be made of varying dimensions and sizes, 25 one which has been satisfactorily utilized had a base portion 76, 30" square and a center elevated portion having a diameter of 24". This embodiment had a shoulder 78 of $\frac{5}{8}$ " as well as an elevated center with a crown of $\frac{3}{8}$ " at 30 the center point 85.

In certain cases if desired the shoulder 78 as shown in Fig. 5 may be omitted and the crown portion 75 caused to merge into the flat edge portions 80 so that there will be a flat horizontal 35 rim adjacent the players while the center portion of the table will be dome-shaped and crowned as indicated in Figs. 4 and 5.

It is to be understood that many changes, alterations and modifications may be made in the 40 invention above described and it is intended to include all such as will fall within the scope of the appended claims.

What is claimed is:

1. A playing card table having a top and leg 45 construction adapted to be used by a card player, said top being provided with a crowned and dome-shaped elevated central portion symmetrically disposed with regard to the edges of the table, whereby said cards may be most readily manipulated and lifted from the table, said table being of square shape and said elevation being spaced sufficiently from the adjacent edges of the table to leave a depressed stacking space immediately in front of the player, and the height of 50 said elevated portion above the edge of the table being about the thickness of a finger.

2. A playing card table having a top and leg 55 construction adapted to be used by a card player, said top being provided with an elevated central portion symmetrically disposed with regard to the edges of the table, whereby said cards may be most readily manipulated and lifted from the table, said table being of square shape and said elevation being spaced sufficiently from the 60 adjacent edges of the table to leave a depressed stacking space immediately in front of the player, and the height of said elevated portion above the edge of the table being about the thickness of a finger.

CHARLES W. MAYER.
